UNITED STATES PATENT OFFICE.

CHARLES D. GERVIN, OF NEW YORK, N. Y., ASSIGNOR TO THE DALE COMPANY, A CORPORATION OF NEW YORK.

CLUSTER-LAMP SOCKET.

No. 897,614

Specification of Letters Patent.

Patented Sept. 1, 1908.

Application filed February 14, 1908. Serial No. 415,857.

To all whom it may concern:

Be it known that I, CHARLES D. GERVIN, a citizen of the United States, residing at the city of New York, in the county of New York 5 and State of New York, have invented certain new and useful Improvements in Cluster-Lamp Sockets, of which the following is a full, clear, and exact description.

My invention relates to cluster lamp sockets, particularly of that type having a substantially hemispherical casing from which the lamps project symmetrically outward at a slight downward inclination. With a device of this class, it is important to have the 10 lamp sockets constructed and supported as simply and cheaply as is consistent with strength and adequate insulating qualities.

By the present invention, I provide a very advantageous construction in these respects, 20 and furthermore, a construction by which a certain additional important function or result is obtained, which, I believe is substantially new in receptacles of this class. This purpose or object, broadly stated, lies in providing a means by which the lamps are adapted to be very simply connected in multiple under ordinary circumstances, corresponding to the nearly universal practical requirements for incandescent lamp circuits, but in 25 which such multiple connection of the lamps is not made absolutely essential, since the lamps may be connected in series multiple, or in entirely separate circuits, if desired.

The series multiple requirement might arise 35 on a 220-volt, or three wire circuit, and the separate circuit requirement might arise where it was necessary to have different numbers of the lamps in a socket illuminated at different times. For example, a socket 40 might have six lamps and be used in a situation where only one, or two, or four of these lamps might be occasionally required. This condition frequently arises where a maximum illumination is required during the 45 early evening hours, while a very slight illumination is sufficient in the late evening and early morning hours when only a few persons are about.

It is therefore the object of my invention 50 to provide a multiple cluster socket adapted to all these needs and requirements, but which, in ordinary use, is as easy to connect up and use as any socket which is specially built for only multiple work.

In the drawings: Figure 1 is a top or plan 55 view of a multiple cluster socket embodying the principles of my invention; and Fig. 2 is an enlarged vertical sectional view of the same with the casing removed.

Referring to the drawings in which like 60 parts are designated by the same reference sign, 1 indicates a casing conveniently of spun sheet metal and which has peripheral openings 2 for the various lamp sockets.

3 designates the threaded or other shells 65 received and held in the openings 2 by means of insulating bushings 4. The various threaded shells are mechanically connected together by a central insulating block 5, which has an additional function of supporting 70 the center contacts. I prefer to make all the center contacts part of a common metallic plate 7 fastened on the lower side of the block 5. A preferred construction is that shown, in which the block 5 is made of frusto-conical form with inclined side faces 8 along which project upwardly the prongs 9 from the plate 7, and which constitute the center contacts for the lamps. The threaded shells are fastened to the block 5 by bifurcated 75 segmental clips 10 which straddle the prongs 9 in sufficiently spaced-apart relation therefrom for the purposes of adequate insulation. At their extremities, the bifurcated portions of the segments 10 are deflected upward and 80 riveted, or otherwise fastened to the threaded shells at points 11.

The essential characteristic of the segmental clips 10 is that they are entirely separate 85 and in insulated relation from one another. 90 Their inner apexes 13 terminate at points slightly short of the central axis of the cluster, and are all separated at such points by a distance adequate for the purposes of insulation. If desired, these inner apexes may 95 normally have a slight upwardly directed tendency so as to be capable of a slight downwardly yielding movement. The separate segmental clips 10 are conveniently fastened 100 on the base 5 by screws or rivets 14, and I further propose to have the bifurcated extremities 10 embrace integral bosses or protuberances 15 on the upper face of said block 5, so as to be absolutely anchored 105 against lateral displacement at this point. I further make use of the bosses or protuberances 15 as accessible points for screws 16 which pass downward through the block 5,

and secure the center contact plate 7 in position. The advantage of this arrangement is two-fold: first, that the screws are always accessible, and, second, an insulating barrier is provided by the bosses 15 separating said screws from the surrounding bifurcated clips 10. One of the bosses or protuberances 15' is much higher than the others, the screw 16' therefore being correspondingly lengthened. 5 This latter screw 16' constitutes a convenient binding post for the common circuit wire connection to the center contact plate 7.

The foregoing construction is substantially complete for certain purposes, but as an article of manufacture, I provide a central screw 15 17 received in a nut 18 within the block, and engaging a loose metallic washer 19 which has sufficient diameter to overlie all of the apices 13 of the bifurcated clips 10. If the 20 screw 17 is tightened downward, the washer 19 is pressed into electrical engagement or connection with all of said clips. On the other hand, when the screw and washer are removed, the clips are entirely separate from 25 one another.

The use and operation is as follows: Ordinarily, the cluster socket will be used for multiple wiring, and simply connected by engaging one circuit wire under the screw terminal 16', and the other circuit wire under the screw 17. When the screws are tightened, all circuit connections are made, since the tightening action effectually depresses the washer 19 into electrical engagement 30 with all the bifurcated segments 10. No further connections or any soldering or taping or compounding are required, and the receptacle, in all senses, is adapted to most convenient work for multiple cluster use. 35 But any party who desires to wire his clusters in a different way is not prevented from doing so. For example, if the lamps are desired in entirely separate circuits, it is merely necessary to connect one return wire to the 40 post 16', and the other separate circuit wires to the individual segments 10. The latter connections will, of course, have to be soldered and compounded, but a slight amount of extra trouble in this unusual use is not at 45 all objectionable. If 110 volt lamps are used with a 220 volt or three-wire circuit, it is merely necessary to connect one circuit wire to half the segments and the other circuit wire to the other half of the segments. If 50 there is a neutral wire, it may be connected to the post 16'; and if there is no neutral wire, this connection is omitted. It will therefore be seen that this form of multiple receptacle is adapted to all needs which arise in ordinary practice, and at the same time, is fitted 55 for the maximum possible convenience for ordinary multiple use.

What I claim, is:—

1. In a cluster socket, a casing having a 65 plurality of shells, metallic clips connected to

said shells and extending in proximity to a common point but out of contact with one another, means connecting said clips together in insulated relation from one another, a single rigid metallic part, and a screw for impelling said part into electrical contact with the proximate ends of all of said clips simultaneously. 70

2. In a cluster socket, a casing, a plurality of shells, clips projecting from said shells toward a common point and insulated from one another, a binding post acting to connect all of said clips together and establish a circuit connection therewith, and means affording center contacts. 75

3. In a cluster socket, a casing, a plurality of shells, clips projecting from said shells toward a common point and insulated from one another, a binding post acting to connect all of said clips together and establish a circuit connection therewith, and a single metallic plate having prongs constituting center contacts for all of said shells. 80

4. In a cluster socket, a casing having threaded shells, bifurcated clips projecting inward therefrom toward a common point and electrically insulated from one another, center contacts projecting between the bifurcated portions of said clips, and means for simultaneously engaging a circuit wire 90 and establishing a connection between said clips. 95

5. In a cluster socket, a casing having threaded shells, bifurcated clips projecting inward therefrom toward a common point 100 and electrically insulated from one another, center contacts projecting between the bifurcated portions of said clips, and a screw and washer for simultaneously engaging a circuit wire and electrically connecting said clips. 105

6. In a cluster socket, a casing having a plurality of shells, bifurcated clips projecting inward therefrom, and electrically insulated from one another, and a single plate having prongs between the bifurcations of said clips 110 and constituting center contacts. 115

7. In a cluster socket, a casing having a plurality of shells, bifurcated clips projecting inward therefrom and electrically insulated from one another, an insulating block connecting said clips and having bosses or protuberances between the bifurcated portions thereof whereby said clips are supported, a plate having prongs constituting center contacts, and means passed through said bosses 120 for holding said terminal plate to said block. 125

8. In a cluster socket, a casing having a plurality of shells, bifurcated clips projecting inward therefrom and electrically insulated from one another, an insulating block connecting said clips and having bosses or protuberances between the bifurcated portions thereof whereby said clips are supported, a plate having prongs constituting center contacts, and means passed through said bosses 130

for holding said center contact plate to said block, one of said means constituting a terminal connection therefor.

9. In a cluster socket, an insulating block 5 of frusto-conical form, a metallic plate on the lower face thereof and having prongs extending upward on the flaring conical surface, separate bifurcated clips on the upper face of said block embracing said prongs, and 10 threaded shells attached to said clips.

10. In a cluster socket, an insulating block of frusto-conical form, a metallic plate on the lower face thereof and having prongs extending upward on the flaring conical surface, 15 bifurcated clips on the upper face of said block embracing said prongs, threaded shells attached to said clips, and means for engaging a circuit wire and establishing an electrical connection between said clips.

20 11. In a cluster socket, a casing having threaded shells, segmental bifurcated clips extending inward therefrom toward a common point and having their inner ends slightly deflected upward, means affording center 25 contacts, a single screw, and means engaged

by said screw for simultaneously making electrical connection with all of the upturned portions of said clips.

12. In a cluster socket, a casing having threaded shells, segmental bifurcated clips 30 extending inward therefrom toward a common point and having their inner ends slightly deflected upward, means affording center contacts, a single screw, and a washer engaged by said screw for simultaneously 35 making electrical connection with all of the upturned portions of said clips.

13. In a cluster socket, threaded shells having separate clips extending inwardly 40 therefrom, an insulating block having bosses or protuberances on its upper face passing through said clips, and means affording center contacts.

In witness whereof, I subscribe my signature, in the presence of two witnesses.

CHARLES D. GERVIN.
